UNITED STATES PATENT OFFICE.

HEINRICH SCHNEIDER, OF WINTERTHUR, SWITZERLAND.

LOCOMOTIVE DRIVEN BY INTERNAL-COMBUSTION ENGINE.

Application filed June 3, 1924. Serial No. 717,555.

To all whom it may concern:

Be it known that I, HEINRICH SCHNEIDER, a citizen of the Republic of Switzerland, residing at Winterthur, Switzerland,

5 have invented certain new and useful Improvements in Locomotives Driven by Internal-Combustion Engines, of which the following is a specification, reference being had therein to the accompanying drawing.

10 This invention relates to improvements in locomotives driven by internal combustion engines and has particular reference to the cooling of such locomotives. The cooling of the cooling water, cooling and lubricating oil on locomotives driven by internal combustion engines of large outputs presents difficulties with the different temperatures of the atmosphere and the different running speeds.

15 The present invention has for its object to provide for an easy control of the temperature of the cooling medium by means of a special arrangement of the radiators, of the fans and of the drive of the latter as well as by a suitable admission and discharge of the necessary large quantities of cooling air.

Locomotives driven by internal combustion engines having radiators at their ends 20 and fans at the inner side of said radiators are known. The present invention consists in the provision of openings in the longitudinal walls of the locomotive between the radiators and the engine room and of guide vanes inserted in said openings and inclined towards the vertical longitudinal centre plane of the locomotive, and in causing the fans to rotate and to reverse their direction of rotation when the locomotive travels in 25 the opposite direction so that for any one of the two directions, in which the locomotive travels, the fan which is at the time being the front fan draws fresh air through the radiator and forces the heated air 30 through the guide vanes pointing in an oblique direction towards the rear, whilst the rear fan draws fresh air through the guide vanes and discharges or forces this air through the radiator. The drive of the 35 fans is effected by the intermediary of a change speed gear and reversing gear so that each fan may be driven at any desired speed or may be kept at a stand-still.

Owing to this arrangement it is rendered 40 possible to provide for a large cooling surface at both ends, which ends cannot be

utilized for any other purpose, whereby the running resistance of the locomotive at the front as well as at the rear end is reduced to a minimum amount.

60 A constructional example of an embodiment of the invention is diagrammatically illustrated by way of example on the accompanying drawings, in which:

Fig. 1 is a vertical section, 65

Fig. 2 is a horizontal section and

Fig. 3 is an end view of the locomotive.

Radiators 1 and 11, for instance of the honeycomb type, are arranged on each end of the locomotive, and at the inner side of 70 the radiators fans 2 and 12 are provided which are driven from the crude oil engine 10 through the intermediary of a change speed and reversing gear 9 and bevel wheel drive 3 and 13. 15 denotes the piping 75 through which the cooling water for the crude oil engine is circulated and forced through the radiators 1 and 11 by the action of the circulation pump 16 driven from the oil engine. 4 and 14 denote the guide vanes 80 which are inclined towards the vertical longitudinal centre plane of the locomotive and inserted in openings provided in the longitudinal walls of the locomotive between the radiators and the engine room 17. 85

When the locomotive travels towards the right (looking at Figs. 1 or 2) the front fan 2 draws fresh air through the radiator 1 and discharges the heated air through the lateral guide vanes 4 into the surrounding 90 atmosphere, whilst the rear fan 12 draws fresh air through the guide apparatus 14 and discharges this air through the radiator 11 towards the rear. A similar operation is obtained when the locomotive travels 95 in the opposite direction.

The larger the amounts of the heat to be dealt with and the higher the temperature of the surrounding atmosphere are the higher is the speed of the fans controlled 100 by means of the change speed gear 9. With a smaller output of the oil engine and with a low temperature of the surrounding atmosphere one or both fans may be stopped. To this end, for instance, a disengageable 105 clutch 18 is provided in the part of the shaft leading from the change speed gear to the fan 2. If the crude oil engine can be reversed for the purpose of changing the direction of travelling of the locomotive the 110 reversing of the rotation of the fans occurs automatically with the reversing of the en-

gine. If the engine rotates always in the same direction the fans are reversed by means of the reversing gear 9.

I claim:

- 5 1. A cooling arrangement for locomotives driven by internal combustion engines, comprising in combination heat exchange devices provided at the ends of the locomotive, a fan arranged on the inner side of each heat 10 exchange device and indirectly driven by the oil engine, guide apparatus inserted in openings provided in the longitudinal walls of the locomotive between the heat exchange devices and the engine room and having 15 vanes inclined towards the vertical longitudinal centre plane of the locomotive, and means to control the direction of rotation of the fans so that, irrespective of the direction in which the locomotive travels, the front 20 fan draws fresh air through the co-ordinate heat exchange device and discharges the heated air through the coordinate guide apparatus whilst the rear fan draws fresh air through the coordinate guide apparatus 25 and discharges the air through its coordinate heat exchange device.

2. A cooling arrangement for locomotives driven by internal combustion engines, comprising in combination radiators provided 30 at both ends of the locomotive, a fan arranged on the inner side of each radiator and indirectly driven by the oil engine, guide vanes inclined towards the vertical longitudinal centre plane of the locomotive 35 and inserted in openings provided in the longitudinal walls of the locomotive, and means adapted to control the direction and the speed of rotation of the fans so that, irrespective of the direction in which the 40 locomotive travels, the front fan draws fresh air through the coordinate radiator and discharges the heated air past the coordinate guide vanes whilst the rear fan draws fresh air past its coordinate guide vanes and dis- 45 charges the air through its coordinate radiator.

3. A cooling arrangement for locomotive driven by internal combustion engines, comprising in combination radiators provided at 50 both ends of the locomotive, a fan arranged on the inner side of each radiator and in- 55 directly driven by the oil engine, guide vanes inclined towards the vertical longitudinal centre plane of the locomotive and in- 60 serted in openings provided in the longitudinal walls of the locomotive, and a change speed and reversing gear interposed in the drive between engine and fans and adapted to control the direction and the speed of ro-

60 tation of the fans so that, irrespective of the direction in which the locomotive travels, the front fan draws fresh air through the coordinate radiator and discharges the heated air past the coordinate guide vanes whilst the rear fan draws fresh air past its 65 coordinate guide vanes and discharges the air through its coordinate radiator.

4. A cooling arrangement for locomotives driven by internal combustion engines, comprising in combination radiators provided 70 at both ends of the locomotive, a fan ar- 75 ranged on the inner side of each radiator, and indirectly driven by the oil engine, guide vanes inclined towards the vertical longi- 80 tudinal centre plane of the locomotive and inserted in openings provided in the longitu- 85 dinal walls of the locomotive, a change speed and reversing gear interposed in the drive between engine and fans and adapted to control the direction and the speed of rotation of the fans so that, irrespective of the direction in which the locomotive travels, the front fan draws fresh air through the coordinate radiator and discharges the heated air past the coordinate guide vanes 90 whilst the rear fan draws fresh air past its coordinate guide vanes and discharges the air through its coordinate radiator, and a disengageable clutch to cut out one of the fans.

5. A cooling arrangement for locomotives driven by internal combustion engines, comprising in combination, radiators provided at both ends of the locomotive, a fan ar- 95 ranged on the inner side of each radiator and indirectly driven by the oil engine, guide vanes inclined towards the vertical longitudinal centre plane of the locomotive and in- 100 serted in openings provided in the longitudinal walls of the locomotive, a change speed and reversing gear interposed in the drive between engine and fans and adapted to control the direction and the speed of rotation of the fans so that, irrespective of the direction in which the locomotive travels, the 105 front fan draws fresh air through the co-ordinate radiator and discharges the heated air past the coordinate guide vanes whilst the rear fan draws fresh air past its coordinate guide vanes and discharges the air 110 through its coordinate radiator, and a dis- 115 engageable clutch to cut out one of the fans, and means to cause a circulation of the cooling medium to be cooled through the radiators.

In testimony whereof I affix my signature

HEINRICH SCHNEIDER.
